LESTER M. WENTLING, OF FOXBURG, PENNSYLVANIA, ASSIGNOR OF ONE-EIGHTH TO RALPH JONES, ONE-EIGHTH TO G. R. REICHART, AND ONE-EIGHTH TO R. M. MONROE, ALL OF PARKERS LANDING, PENNSYLVANIA; ONE-EIGHTH TO C. E. HARRINGTON, OF KITTANNING, PENNSYLVANIA, AND ONE-EIGHTH TO ALBERT NEVEL, OF FOXBURG, PENNSYLVANIA.

GUARD RAIL.

Application filed January 25, 1923. Serial No. 614,812.

To all whom it may concern:

Be it known that I, LESTER M. WENTLING, a citizen of the United States of America, residing at Foxburg, in the county of Clarion and State of Pennsylvania, have invented new and useful Improvements in Guard Rails, of which the following is a specification.

The object of the invention is to provide a safety guard rail for railroad tracks which is adapted not only to perform the usual function of a guard rail but to serve as a substantial reinforcement for the track rail in the matter of securing the same against displacement or deflection under a track spreading strain; furthermore to provide a guard rail which in connection with a base plate suitable for seating the track rail is adapted to definitely lock the track rail against spreading action while permitting freedom of longitudinal movement incidental to variations in length due to changes in temperature, while maintaining a fixed position of the guard rail in reference to the ties and to the base plates carried thereby; and furthermore to provide a guard rail which is not open to the objection ordinarily experienced that the heels of boots or shoes of pedestrians traversing the tracks are subject to being caught between the guard rail and the head of the track rail; and with these objects in view the invention consists in a construction and combination of parts of which a preferred embodiment is shown in the accompanying drawings, wherein:—

Figure 1 is a plan view of a section of a railway track including a guard rail and related parts constructed in accordance with the invention.

Figures 2, 3 and 4 are sectional views respectively on the planes indicated by the lines 2—2, 4—4 and 3—3 of Figure 1.

Figure 5 is a plan view of one of the bed or base plates.

The guard rail 10 of which the upper edge 11 is arranged in the plane of the tread 12 of the track rail 13 is channeled as indicated at 14 for the flange of a wheel traversing the tread of the track rail and is provided with a lateral wing 15 which snugly engages and fills the space between the head and the foot of the track rail so as to con-

stitute an interlocking engagement with the track rail serving to brace the latter substantially throughout its height. The track and guard rails, thus interlocked under rails permitting of the longitudinal movement of the track rail incidental to expansion and contraction thereby by changes in temperature are supported by bed plates or base plates 16 secured to the ties 17 and having depressed seats 18 bounded laterally by shoulders 19 formed by terminal enlargements 20 on the plate. The bed plate is secured to the tie by means of spikes engaging openings 21 in the plate, the staggering thereof obviously being designed to minimize the tendency of the spikes to split the tie, and supplemented by an additional spike for which purpose a supplemental opening 22 is formed at the outer end of the plate or at that end which is outside of the track as an additional security and which is preferably arranged opposite the intervals between the outer and inner spike openings 21. The bed plate is further provided within the seat 18 with openings 23 for the reception of rivets 24 depending from the guard rail and serving to definitely anchor the latter to the bed plate and therefore to the ties by which the bed plates mutually supporting a guard rail are carried. The spike openings 21 are formed in the shoulders constituting the thickest portion of the bed plate and break into the seat so that the heads of the spikes which are directed inwardly or toward the rails (to-wit the interlocked track and guard rails) and which overhang the feet of said rails, may directly bear upon and clamp said bases to the bed plate.

Furthermore the guard rail is preferably thickened horizontally toward its extremities and the channel 14 formed therein is correspondingly flanged so as to present no terminal interval which is likely to engage with a foot or shoe or object approaching the same. The lateral wing 15 of the guard rail, as shown clearly in Figure 3, conforms to and engages the full contour of the fish plate receiving recess of the track rail and acts to retain the track rail against tilting inwardly or displacement upwardly even in the absence of spiking means on the

outer portion of the base of the track rail and yet permits the track rail to expand longitudinally in parallelism with the guard rail without in any way affecting or changing the relation of the guard rail relative to the frog. In practically all devices, the guard rail is fastened to the track rail and, furthermore, the guard rails in all other devices do not conform to the fish plate receiving recess of the track rail. In the present device, due to the track rail receiving seat with its opposed terminal shoulders, there is no chance for the track rail to be displaced and, therefore, preventing destroying the gauge between the two rails as well as preventing destroying the gauge between the ball of the track rail and the ball of the guard rail, the guard rail at all times remaining in a uniform position relative to the frog while the track rail is capable of expansion and contraction longitudinally in parallelism with the guard rail.

Having described the invention, what is claimed as new and useful is:—

1. In a guard rail, the combination with bed plates provided with depressed seats including terminal shoulders, of a track rail with its base engaging the bottoms of the seats, with one edge of the base in engagement with corresponding terminal shoulders at the outer portions of the bed plates, means retaining the outer edges of the base in engagement with the outer shoulders, a guard rail with its base engaging between the inner edge of the track rail and the

shoulders at the inner ends of the bed plates, and means for retaining the guard rail base in engagement with the inner shoulders and fastening the bed plates to the ties, said guard rail provided with a lateral wing extending longitudinally thereof and conforming throughout its length with and engaging the fish plate receiving recess of the track rail, thereby retaining the track rail in position and yet permitting it to expand and contract longitudinally in parallelism with the guard rail without effecting any change of the guard rail with relation to a frog adapted to oppose the guard rail.

2. In a guard rail construction, the combination with bed plates provided with depressed seats, of a guard rail with its base engaging said seats adjacent their terminals at the inner ends of the plates, means for fastening the base of the guard rail permanently to the bed plates, said guard rail having a lateral wing facing outwardly with its upper face a substantial distance below the ball of the guard rail, and a track rail with its base engaging said seats, with one side of its flange conforming to and engaging under said lateral wing which conforms to and engages with the fish plate receiving recess of the track rail, whereby the track rail may expand and contract longitudinally in parallelism with the rail which remains in uniform position with relation to an opposed frog.

In testimony whereof I affix my signature,
LESTER M. WENTLING.
